US00D720367S

(12) **United States Design Patent**
Woo

(10) **Patent No.:** **US D720,367 S**
(45) **Date of Patent:** **** Dec. 30, 2014**

(54) **DISPLAY SCREEN WITH GRAPHICAL USER INTERFACE**

(71) Applicant: **Microsoft Corporation**, Redmond, WA (US)

(72) Inventor: **Aaron N. Woo**, Bellevue, WA (US)

(73) Assignee: **Microsoft Corporation**, Redmond, WA (US)

(**) Term: **14 Years**

(21) Appl. No.: **29/471,242**

(22) Filed: **Oct. 30, 2013**

Related U.S. Application Data

(62) Division of application No. 29/384,444, filed on Jan. 31, 2011.

(57) **CLAIM**

The ornamental design for a display screen with graphical user interface, as shown and described.

DESCRIPTION

FIG. 1 is a front view of a display screen with graphical user interface showing my new design;

FIG. 2 is a front view of a display screen with graphical user interface showing a second embodiment of my new design;

FIG. 3 is a front view of a display screen with graphical user interface showing a third embodiment of my new design;

FIG. 4 is a front view of a display screen with graphical user interface showing a fourth embodiment of my new design;

FIG. 5 is a front view of the display screen of FIG. 1 shown on a device;

FIG. 6 is a front view of the display screen of FIG. 2 shown on a device;

FIG. 7 is a front view of the display screen of FIG. 3 shown on a device; and,

FIG. 8 is a front view of the display screen of FIG. 4 shown on a device.

The broken line showing of the remainder of the display screen in FIGS. 1-8 and the remainder of the device in FIGS. 5-8, is for environmental purposes only and forms no part of the claimed design.

1 Claim, 8 Drawing Sheets
